UNITED STATES PATENT OFFICE.

EMIL HOFFMANN, OF COLOGNE, GERMANY.

METHOD FOR FORMING A METALLIC CROSSTYING OF PACKAGES.

Application filed February 20, 1920. Serial No. 360,183.

To all whom it may concern:

Be it known that I, EMIL HOFFMANN, a citizen of the German Republic, residing at Cologne, Marienburg Lindenallee 62, in the Republic of Germany, have invented certain new and useful Improvements in a Method for Forming a Metallic Crosstyng of Packages (for which I have filed applications as follows: in Germany January 10, 1918; in Belgium January 31, 1918; in Austria May 21, 1918; in Denmark December 16, 1918; in Sweden December 19, 1918; in Norway December 23, 1918; in France January 18, 1919; in Hungary February 8, 15 1919; in Holland April 1, 1919; in Switzerland April 23, 1919; in Czecho-Slovakia April 24, 1919; in Argentina July 25, 1919; in Spain April 26, 1919; in Great Britain August 8, 1919; and in Brazil September 12, 20 1919), of which the following is a specification.

The present invention relates to improvements in metallic package-ties and particularly to a new method for cross-tying of packages. This method consists in pulling the end-portions of the metallic tie or ties being laid crosswise around the package through a connecting-piece (ring or the like), bending the ends down to the stretched 25 part of the ties and joining said end-portions with the stretched parts by means of punching and pressing the punched parts together or assembling the parts by pinching or in a similar manner. The essential condition 30 of this connection is to have it performed in such a manner that its disengagement is only possible by force. A means for this purpose is for example the above mentioned joint by punching and pressing. This joint 35 has been known for assembling free ends of package-ties. The invention consists in the new method of application of these joints to obtain a strong and good stretched package-tying.

40 This cross-tying affords not only a security against untying but also a protection against fraudulent infringements as the locking connection cannot be restored in due order after being once destroyed by force.

45 Metallic package-ties have been used up to now with more or less complicated means for securing the connection of the end-portions and making the tying unremovable. Also the connections of these known package-ties

are not performed in such a manner that a 55 disengagement is only possible by force.

The package-tie according to the invention is so fast as to be unremovable and makes a special sealing dispensable. Still more unremovable becomes the package-tie 60 of the invention by uniting (by pinching or the like) also the crossing parts of that side of the package, where the straps are superposed in flat condition.

Fig. 1 is a perspective view of a package 65 with the improved metallic tie applied thereto.

Fig. 2 is a plan of the same.

Fig. 3 is a perspective view of a form of tie shown in package forming relation, the 70 package being omitted.

The metallic tie (for instance a steel-tie) 75 *b* is drawn through the opening of the connecting-piece *a*, which is shown as a ring and laid crosswise around the package. The end-portions *d* and *e* coming back to the ring-side of the package are drawn through the ring with a strong pull and bent down to the straps. The connection of these end-portions *d* and *e* with the straps is then performed by pinching both parts together in a manner that a disengagement is only possible by force. A means for this purpose is the known punching of tongue-like pieces 80 from the overlapping tie-parts and pressing 85 the parts together.

The tying may also be performed in a manner that first one end-portion of the tie, say *d*, is fastened to the ring *a*. Then the tie is laid around the package and drawn 90 through the ring *a* at *c*; from this point it is conducted again at a right angle around the package and drawn with strong pull with its end-portion *e* through the ring *a* in order to be joined as before mentioned. 95

Also two separate ties are applicable one tie of which is fastened with its one end-portion to the connecting-piece and the other crosswise fastened to the first one. The three free ends are now drawn through the 100 connecting piece, bent down and joined with the stretched tie parts as before mentioned.

By connecting the crossing-parts of the tie in the aforesaid or any other manner the tying will become unremovable.

105 The connecting-piece may also be a piece of sheet metal provided with slots or other openings. It may be fastened with cramps

or other means to the package. This fastening is for instance to be made by a piece of sheet-metal being attached to the under-side of the package and having cramps to 5 fasten the connecting piece.

I claim:

1. A method for forming a metallic cross-tying of packages consisting in drawing the end-portions of the metallic tie, being laid 10 crosswise around the package, through a connecting-piece, bending said end-portions down to the stretched parts of the tie and joining these overlapping parts in such a manner that disengagement is only possible 15 by force, substantially as described.
2. A method for forming a metallic cross-tying of packages consisting in drawing the end-portions of the metallic tie, being laid crosswise around the package, through a 20 connecting-piece, bending said end-portions down to the stretched parts of the tie and joining these overlapping parts as well as the overlapping parts at the crossing-point 25 in such a manner that disengagement is only possible by force, substantially as described.
3. A method for forming a metallic cross-tying of packages consisting in fastening

one end-portion of the metallic tie to a connecting-piece, laying the tie around the package, drawing it again through the said 30 connecting-piece, laying the rest of the tie from the connecting-piece at right angles so as to cross the first laid part, drawing the free end-portion through the said connecting-piece, bending said end-portion down to 35 the stretched part of the tie and joining these overlapping parts in such a manner that disengagement is only possible by force, substantially as described.

4. A method for forming a metallic cross 40 tying of packages, consisting in providing a connecting piece through which the terminals of the tie are passed, stretched, and lapped, the lapped terminals being permanently secured together in a manner to prevent 45 their disengagement except through the application of force.

In testimony whereof I affix my signature in presence of two witnesses.

EMIL HOFFMANN.
